UNITED STATES PATENT OFFICE

2,537,024

HEAT EXCHANGER FINNED TUBE

Thomas J. Bay, United States Navy

Application December 2, 1946, Serial No. 713,451

5 Claims. (Cl. 257—262.2)

(Granted under the act of March 3, 1883, as amended April 30, 1928; 370 O. G. 757)

1

This invention relates to improvements in heat exchangers and more particularly to the use of finned tubes.

An object of this invention is to improve the heat transfer rate of tubes in heat exchangers with the ultimate result of reducing the total number of tubes required.

Another object is to make possible small light-weight heat exchangers and condensers.

Another object is to provide a simple means of securing the fins to the tubes.

A further object is to provide efficient means of securing the tubes in supports.

Finned tubes, according to the present invention, may be used in double tube type heat exchangers and tubular heat exchangers including surface condensers for steam and refrigerants. Improved heat exchangers of my design are particularly suitable for use in Diesel and steam driven naval vessels.

The use of fins attached to the outside surface of a tube increases the effective heat transfer surface of the tube which improves the heat transfer rate through the tube. Finned tubes, however, in heat exchangers and condensers present the difficulty of securing the ends of the tubes in tube sheets dividing the two mediums to be treated.

The addition of fins to a tube increases the overall diameter of the tube. As a result, the hole in the tube sheet through which the tube must pass in order to be installed in the heat exchanger is too large to permit the tube to be secured by conventional methods. The present invention provides for overcoming this difficulty by expanding and bellng the ends of the finned tube into a metallic bushing with an outside diameter slightly greater than the overall diameter of the tube with fins. This bushing is secured in the tube sheet by packing, soldering or silver brazing.

The invention also resides in certain novel features of component structure and arrangements which facilitate the carrying out of the foregoing objects and which contribute both to the simplicity of the device and to the reliability of operation as well as to the ease and expeditious manner of construction.

Other objects and advantages of the invention will become apparent from the following detailed description taken in connection with the accompanying drawings in which:

Fig. 1 is a longitudinal partial cross section showing a double tube construction.

2

Fig. 2 is a longitudinal partial cross section showing a single tube construction.

Fig. 3 is a longitudinal partial cross section showing an alternative arrangement for securing the tube in single tube construction.

Fig. 4 is a longitudinal partial cross section of another single tube construction.

While the invention is susceptible of various modifications and alternative arrangements, I have shown in the drawings and will herein describe in detail the preferred embodiments. It is to be understood, however, that I do not intend to limit the invention by such disclosure for I aim to cover all modifications and alternative arrangements falling within the spirit and scope of the invention as defined in the appended claims.

Fig. 1 shows the tube 11 carrying an extended spiral wire fin 12 which is secured by bushing 13 of constant diameter in a tube sheet 14 of a double tube type heat exchanger. The fins 12 are formed by a small diameter spiral wrapped coil of suitable wire through which a binding-wire 15 has been threaded. The binding wire is wound several times around the tube 11 beyond the end loop of the coil and is secured to the bushing 13 by an escutcheon pin 16. The end of tube 11 is belled and expanded into bushing 13 which has an outside diameter slightly greater than the overall diameter of the tube with fins.

To insure positive contact between the coil 12 forming the fins and the tube 11, the finned tube assembly is tinned. The bushing 13 is secured in the tube sheet 14 by packing 17. The double tube arrangement is provided by a surrounding tube 18 which is expanded into the second tube sheet 19. A similar arrangement may be provided at the other end of tubes 11 and 18. The tube 18 is of slightly larger diameter than the coiled helical wire 12 so as to confine any liquid flowing between the two tubes 11 and 18 to close proximity to the coil 12. The fluid to be cooled flows through tube 11, and the cooling fluid flows through tube 18 and the aperture between plates 19 and 14 in a manner well known in the art.

In Fig. 2 a tubular type heat exchanger without the outside tube is shown. The finned tube 11 with spiral coil 12 and binding wire 15 is secured as in Fig. 1 by bushing 13 and packing 17 in tube sheet 14.

In Fig. 3 an alternative method of securing a finned tube in a tube assembly sheet is shown. The bushing 13 is secured directly to the tube sheet 14 by soldering, silver brazing or welding.

It may also be threaded if desired.

In Fig. 4 is shown an alternative arrangement for securing one end of a finned tube 11A, the other end being supported by one of the arrangements described above for finned tube 11. The belled end 20 of tube 11A fits a complementary opening in tube sheet 21. Fin tubes of type 11A are installed in a heat exchanger or condenser by inserting the bushed ends through a tube sheet such as 14 which has been drilled for the bushed end finned tubes. The end of the fin tube 11A not having a bushing is expanded and belled into the tube sheet 21.

In the case of tubes packed at both ends, the invention provides that the tube joint at one end may be so constructed as to provide threads or serrations in the stuffing box or hole in the tube sheet 14 and in the metallic bushing 13 so that the packing 17 between these parts will be restrained thereby preventing any axial movement of the finned tube due to expansion.

The tubes may have the same type of support at both ends or various combinations of the supports shown may be used.

The invention described herein may be manufactured and used by or for the Government of the United States of America for governmental purposes without the payment of any royalty thereon or therefor.

I claim:

1. In a heat exchanger the combination of a tube, a hollow coil surrounding the tube, a binding element inside the coil, plate-supported bushings at each end of said tube, said element being fastened to said bushings.

2. A tube assembly adapted for use in a heat exchanger, said assembly comprising: a tube; a hollow coil surrounding said tube; bushings fixed to each end of said tube and adapted to be plate-supported; and a binding element inside of said coil and fastened to said bushings.

3. A tube assembly for use in a heat exchanger, said assembly comprising in combination: a tube, a hollow coil surrounding said tube and fixed in positive contact therewith along the longitudinal extent thereof; a bushing adapted to be supported by a plate and fixed to each end of said tube; said coil being constructed and arranged to project

outwardly from said tube to an extent not greater than the diameter of said bushing; and a binding element fastened to each of said bushings and extending inside of said coil.

4. In a heat exchanger, in combination: a tube; a hollow coil surrounding said tube and fixed in positive contact therewith along the longitudinal extent thereof; a plate supported bushing fixed to each end of said tube; said coil being constructed and arranged to project outwardly from said tube to an extent not greater than the diameter of said bushing; and a binding element fastened to each of said bushings and extending inside of said coil.

5. In a heat exchanger, in combination: a tube; a hollow coil surrounding said tube and fixed in positive contact therewith along its longitudinal extent; a tube sheet; an aperture therein; a packing recess in the outer face of said sheet positioned adjacent to and having a diameter greater than said aperture; a bushing fixed to one end of said tube and mounted in said aperture; a packing held in said recess and arranged to seal said bushing in said aperture; and a binding element fastened to said bushing and extending inside said coil; said coil being constructed and arranged to project outwardly from said tube to an extent not greater than the diameter of said bushing.
